Inventor:

Sylvanus B. Hitt.

UNITED STATES PATENT OFFICE.

SYLVANUS B. HITT, OF WATERLOO, IOWA, ASSIGNOR OF TWO-THIRDS HIS
RIGHT TO RICHARD T. HITT AND ROBERT W. CHAPMAN, OF SAME PLACE.

IMPROVEMENT IN FIFTH-WHEELS FOR WAGONS AND CARRIAGES.

Specification forming part of Letters Patent No. 158,212, dated December 29, 1874; application filed
August 25, 1874.

To all whom it may concern:

Be it known that I, SYLVANUS B. HITT, of the city of Waterloo, Black Hawk county, and State of Iowa, have invented certain Improvements in Wagon-Circles or Fifth-Wheels for Platform Spring Wagons, Buggies, and Carriages, of which the following is a specification:

This invention relates to certain improvements upon that class of fifth-wheels for vehicles in which the lower section is provided with conical rollers upon which the upper section bears and turns, for the purpose of rendering such class of devices more efficient and perfect in operation.

The object of this invention is to improve such class of devices, whereby a tight and close-fitting union between the upper and lower sections is effected, thereby preventing the entrance of dirt between the parts, which would impair the proper working of the parts; and, further, the two sections of the fifth-wheel will act as guides to each other and prevent any lateral displacement.

To this end my invention consists in constructing the lower section of the fifth-wheel, which carries the rollers, with a vertical flange on its outer periphery, and constructing the upper section with a downwardly-projecting flange on its inner periphery, whereby, when the two parts are in their proper position, there will be a tight and close-fitting union between the two, preventing the entrance of dust and protecting and concealing the rollers from injury, and rendering the operation of the device perfect and very efficient in operation; and at the same time the construction of the said sections is such that they act as guides to each other when the one is turning, as will be hereinafter described.

In the accompanying drawings, Figure 1 represents the bolsters and platform of a vehicle having my improvements applied thereto; Figs. 2 and 3, detached views of the lower and upper sections of the fifth-wheel, and Fig. 4 a longitudinal central section.

The bolsters and platform are, in the present instance, united together by a flanged plate,

i, secured to the bolsters, and having a central opening into which fits a circular projection, *h*, on a flanged plate, *g*, bolted to the platform-gear, thereby permitting the latter to be turned, and preventing wear between the two parts, this method of uniting the platform and bolsters having been found to be very reliable and efficient. The upper section of the fifth-wheel is constructed with a horizontal flange, *E*, and a downwardly-projecting flange, *f*, on its inner periphery, forming an angle-iron, which is bolted to the bolsters, as shown, and the lower section of the fifth-wheel is constructed of a flat ring, having on its outer periphery a vertical flange, *a*, and cast or formed with segmental cavities, within which the rollers *d* are journaled in radial lines drawn from the center of the fifth-wheel. When the two parts of the fifth-wheel, constructed as above described, are in their proper position, the flange *f* on the upper section will project down to, or nearly to, the inner periphery of the lower section, and the vertical flange *a* on the latter will project slightly above the lower edge of the horizontal flange *E* of the upper section, whereby a tight and close union between the two is effected, and the rollers will be entirely concealed and protected. Further, by this tight and close fitting of the sections, the entrance of dirt and other matter which would impair the proper operation of the device is prevented, and by the flanges described the sections are prevented from any lateral movement, and act as guides to each other.

What I claim is—

The lower section of a fifth-wheel, constructed with a vertical flange, *a*, and segmental cavities, in which the rollers *d* are journaled, in combination with the upper section constructed with the downwardly-projecting flange *f*, substantially as and for the purpose specified.

SYLVANUS B. HITT.
